UNITED STATES PATENT OFFICE.

JULES H. VENON, OF NEW YORK, N. Y.

DESIGN FOR A DISH.

Application filed January 6, 1922. Serial No. 63. Term of patent 7 years.

To all whom it may concern:

Be it known that I, JULES H. VENON, a citizen of the United States, and resident of the city, county, and State of New York, have invented a new, original, and ornamental Design for Dishes, of which the following is a specification, reference being had to the accompanying drawing, forming part thereof.

The figure of the drawing is a plan view showing my new design.

The important feature of my design is the decoration shown in the center of the dish in the drawing which may be applied to dishes of a set generally.

I claim:—

The ornamental design for a dish, as shown.

JULES H. VENON.
